4 Sheets-Sheet 4

FIG. 1.

INVENTOR
PHILIP A. JACKSON,

By Paulmin Paulmin

ATTORNEYS

UNITED STATES PATENT OFFICE.

PHILIP A. JACKSON, OF DAYTON, OHIO, ASSIGNOR TO THE EGRY REGISTER COMPANY, OF DAYTON, OHIO, A CORPORATION OF OHIO.

AUTOGRAPHIC REGISTER.

Application filed July 6, 1925. Serial No. 41,471.

My invention relates to autographic registers.

The object of my invention is to provide an autographic register in which, by means 5 of a reciprocating or a continuously moving actuating handle, I am enabled to secure the successful clamping of the sheets during the writing operation, the ejecting of the sheets, the projection of aligning pins into the 10 sheets through suitable apertures at a predetermined interval at the end of the ejecting operation and simultaneously rendering the ejecting means inoperative, and reclamping the sheets upon the withdrawal of the 15 aligning means so that the sheets will be reclamped in aligning position for another writing operation.

My particular object is to push the pins upwardly through the paper in this combination and sequence of operations, the pins riding on the bottom of the bottom sheet.

Referring to the drawings:

Figure 1 is a side elevation of the register;

Figure 2 is a plan view with the cover removed;

Figure 3 is a detail view showing the rollers in clamping position with the pins out of engagement with the sheets;

Figure 4 is a similar view showing the pins in engagement with the sheets and the rollers in spread position;

Figure 5 shows a view with the cams in inoperative position and the rollers in engagement with the paper;

Figure 6 shows the cams in operative position with the rollers spread apart;

Figure 7 is a section on the line 7-7 of Figure 2;

Figure 8 is a section on the line 8-8 of Figure 2; and

Figure 9 is a section on the line 9-9 of Figure 2.

Referring to the drawings in detail, 1 is the base of the register having the side walls 2 and end walls 3 and 4. A lid 5 is provided with a writing opening 6. The forward end of the lid has an arched shaped member 7 to contain the upper roller. The side walls 2

50 are projected upwardly at this point with ears 8 provided with slots 9 for carrying the ends of the upper roller shaft 10 to permit it to move upwardly and downwardly.

This upper roller is designated 12 and the gear which it carries is designated 13. This gear meshes with a lower gear 14 on the lower roller 15 which is carried on the shaft 16 journaled in the side walls 2 of the register. Loosely mounted on this lower shaft are the plates 17 at either end of the shaft 16 one side of which carries the raised cam portion 18, the other the projecting arm 19. These projecting arms are connected together by a bar 20 which is provided with a weight 21. This plate 17 is provided with a stop member 22 to limit its rotation in one direction which is in the upward direction for the pins. Pivotally supported on this plate to one side of the stop on pins 23 are the links 24 which depend downwardly and rearwardly to connect with the vertical members 25 at 26 on the frame arms 27 which are pivoted in the forward end of the machine on either side as at 28. Between these depending arms 25 there is the bar 29 which carries the pins 30 beneath the paper. These pins are tapered on their forward sides very materially and slightly tapered on their rear sides. They are adapted to enter the file punch perforations customarily found in autographic register sheets and are forced into the apertures at a predetermined interval as hereinafter described in aligning purposes at the time the sheets are free due to the fact that the rollers 12 and 15 are not in engagement with the sheets at that time.

These rollers are cut away as at 31 and 32 to permit the pins to pass through the rollers. The rollers are knurled as at 33, 90 to facilitate engagement with the sheets. These rollers are geared together as herein-after explained and are actuated by a suitable train of gears. Mounted on the shaft 34 on the inside of one of the register walls is a gear 35. This gear 35 meshes with a gear 36 on a stub shaft 37 which carries on the same shaft a somewhat larger internally disposed gear 38 which in turn meshes with a pinion 39. This pinion engages with another pinion 40 which in turn engages with the gear 14.

On the outside of the register the gear 41 is mounted loosely on the shaft 34. On the end of the shaft 34 is carried a ratchet member 42 which is provided with cut away por-

tions 43 and 44. A pawl 45 pivoted at 46 on the gear 41 is adapted to have its nose engaged with the shoulder formed by one of these cut away portions in order to insure 5 the gear 41 and the shaft 34 turning together during a portion of the stroke of the handle 47. A spring 48 is attached to the pawl and to the gear 41 to insure the pawl falling into the cut away portion when it 10 comes opposite to it on the ratchet 42. The teeth of the gear 41 are engaged by the segmental gear 49. The segmental gear 49 is carried by the handle 47. Thus with one stroke of the handle the mechanism will be 15 operated so that the paper sheets will be ejected and at the stroke of the handle in the other direction the ejecting rollers will remain idle due to the fact that the gear 41 is not turning with the shaft 34. This handle 20 is limited in one direction by the stop 50 and in the other direction by an arm 51 which engages with one of the cut away portions 43 or 44. Also carried on this handle is an inwardly projecting pin 52 25 which engages with a finger 53 pivotally mounted on a shaft 54 which shaft carries another finger 55 internally of the register, the free end of which engages with the bar 20 for rotating the weighted frame members and pins and cams. 56, 57 and 58 indicate the several superimposed sheets having 30 apertures 59.

Operation.

35 When the handle is in its forward position at rest the rollers will be in clamping engagement with the aligned sheets and the pin 52 will hold the weighted arms 20 upwardly and the pins and cams in their inoperative position. As the handle is drawn 40 backwardly the sheets will be ejected by the ejecting rollers and the pins will be allowed to engage with the under surface of the sheets riding against the under surface due 45 to the weight 21 on the weighted arm 20 causing the pins to press against the under side of the sheets. As soon as the perforations transversely arranged in the sheets, which are the usual file punch perforations, 50 appear over the pins, the pins are pushed through the sheets by the weight 21. Simultaneously the cams are carried between the rollers to spread the rollers and render them inoperative. The clearance between the tips 55 of the pins and the file punch holes in the sheets is substantially $2/16''$ and the major portion of this clearance is, of course, to the rear of the pins so in case the sheets are moved slightly by the rollers before they 60 are freed from the sheets, the sheets will not be pulled against the pins and the sheets torn. As soon as the pins align the sheets 65 the end of the stroke is reached and the handle is returned to its initial position. When it returns to its initial position the

pin 52 reengages the lever 53 thereby depressing the pins, pulling them from the sheets, and allowing the rollers to clamp the sheets in aligned position for another operation.

70 It will be understood that I desire to comprehend within my invention such modifications as may be necessary to adapt it to varying conditions and uses.

Having thus fully described my invention, 75 what I claim as new and desire to secure by Letters Patent, is:—

1. In an autographic register containing a plurality of superimposed sheets interleaved with carbon paper and having spaced 80 perforations, an actuating means, a pair of superimposed ejecting rollers operated by said actuating means during a portion of its stroke, aligning pins located beneath the sheets adjacent to one of the rollers, cams 85 loosely mounted at either end of said rollers, means to carry said pins connected to said cams so that they move together synchronously, and means adapted to push said pins upwardly and to rotate said cams to spread 90 the ejecting rollers, and means to control said cams and pins according to the movement of the actuating means.

2. In an autographic register containing a plurality of superimposed sheets interleaved with carbon paper and having spaced 95 perforations, an actuating means, a pair of superimposed ejecting rollers operated by said actuating means during a portion of its stroke, aligning pins located beneath the sheets adjacent to one of the rollers, cams 100 loosely mounted at either end of said rollers, means to carry said pins connected to said cams so that they move together synchronously, and means adapted to push said pins upwardly and to rotate said cams so as to 105 spread the ejecting rollers, means to control said cams and pins according to the movement of the actuating means, said means to push said pins and cams into operative position 110 consisting of a weight.

3. In an autographic register containing a plurality of superimposed sheets interleaved with carbon paper and having spaced 115 perforations, an actuating handle gearing adapted to actuate ejecting rollers, ejecting rollers geared to one another, means to permit said gearing to be operated during a portion of the stroke of the handle and to remain inoperative during another portion of the stroke of the handle, a frame carrying pins, means at either end of the rollers carrying cams, means connecting said pin frame and cam carrying means, a weighted member 120 connected to said cam carrying means to actuate said cams, pin carrying frame, means to actuate said weighted member to render it inoperative and the pins and cams inoperative, and means on said actuating handle 125 adapted to engage with said last mentioned 130

means to control it, whereby the handle will successively bring about in the register a clamping of the paper sheets during the writing operation and a removal of the pins 5 from the sheets and ejecting of the sheets, realignment of the sheets and a reclamping of the sheets with a removal of the aligning means such as pins from the sheets.

4. In an autographic register having a 10 pair of ejecting rollers, a pair of members mounted on either end of one of said rollers, bars connecting said members, one of said bars carrying a weight and the other carrying upwardly projecting aligning pins, 15 cams mounted on either of said members for spreading the rollers, means to actuate the rollers during a predetermined period, means to control the operation of the weighted member to in turn control the operation 20 of the cams and pins, whereby the sheets will be alternately ejected, aligned, and clamped.

5. In an autographic register having a 25 pair of ejecting rollers, a pair of members mounted on either end of one of said rollers, bars connecting said members, one of said bars carrying a weight and the other carrying upwardly projecting aligning pins, cams mounted on either of said members for spreading the rollers, means to actuate the 30 rollers during a predetermined period, means to control the operation of the weighted member to in turn control the operation of the cams and pins, whereby the sheets will be alternately ejected, aligned, and clamped, 35 one of said rollers being cut away to receive said pins.

6. In an autographic register having a 40 pair of ejecting rollers, a pair of members mounted on either end of one of said rollers, bars connecting said members, one of said bars carrying a weight and the other carrying upwardly projecting aligning pins, cams mounted on either of said members for spreading the rollers, means to actuate the 45 rollers during a predetermined period, means to control the operation of the

weighted member to in turn control the operation of the cams and pins, whereby the sheets will be alternately ejected, aligned, and clamped, one of said rollers being cut 50 away to receive said pins, said pins being tapered for progressive alignment of the sheets without tearing.

7. In an autographic register having a 55 pair of ejecting rollers, a pair of members mounted on either end of one of said rollers, bars connecting said members, one of said bars carrying a weight and the other carrying upwardly projecting aligning pins, cams mounted on either of said members for 60 spreading the rollers, means to actuate the rollers during a predetermined period, means to control the operation of the weighted member to in turn control the operation of the cams and pins, whereby the sheets 65 will be alternately ejected, aligned, and clamped, one of said rollers being cut away to receive said pins, said pins being tapered for progressive alignment of the sheets without tearing, said pins being so arranged that 70 they will enter the sheets with the maximum clearance to the rear of the pins between the pins and the margin of the sheets.

8. In an autographic register having a 75 pair of ejecting rollers, a pair of members mounted on either end of one of said rollers, bars connecting said members, one of said bars carrying a weight and the other carrying upwardly projecting aligning pins, cams mounted on either of said members for 80 spreading the rollers, means to actuate the rollers during a predetermined period, means to control the operation of the weighted member to in turn control the operation of the cams and pins, whereby the sheets will 85 be alternately ejected, aligned, and clamped, and stops associated with the cam members to limit the movement of the cams in one direction.

In testimony whereof, I affix my signature. 90

PHILIP A. JACKSON.
